CALVERT B. COTTRELL, 3D, OF WESTERLY, RHODE ISLAND, ASSIGNOR TO C. B. COTTRELL & SONS COMPANY, OF WESTERLY, RHODE ISLAND, A CORPORATION OF DELAWARE

BED AND CYLINDER PRINTING PRESS

Application filed May 16, 1931. Serial No. 537,794.

One object of my invention is to provide means for more evenly inking the form on the bed of a bed and cylinder printing mechanism where the form and its bed reciprocate in a right line, said means including an inking mechanism having its distributing and form rollers driven continuously in one direction independently of the bed drive, said form rollers being automatically raised out of the path of the form on one stroke of the bed.

5 A practical embodiment of my invention is represented in the accompanying drawing in which:

10 Fig. 1 represents a side elevation of my improved bed and cylinder printing press, the parts being shown in full lines in the positions they assume just after the bed and cylinder have started on their forward or printing stroke, and in dotted lines in the positions the parts assume at the end of the said forward or printing stroke;

15 Fig. 2 represents a diagrammatic view of the impression cylinder and its adjacent parts in the positions they assume just as the impression cylinder has started on the first revolution of its forward or printing stroke and has taken at its under side a sheet from the feeder;

20 Fig. 3 represents a similar view showing the positions of the parts as the impression cylinder has completed its forward or printing stroke of about one and one-half revolutions and is ready to start on its reverse or non-printing stroke for transferring the printed sheet tail end first from the upper side of the cylinder; and

25 Fig. 4 represents a similar view showing the positions of the parts as the impression cylinder has completed about one revolution of its reverse or non-printing stroke and the printed sheet has been transferred from the cylinder.

30 The main frame of the printing press is denoted by 1. The form bed 2 and its form 3 are fitted to reciprocate in a right line in the main frame. The inking mechanism for the form is shown as comprising an ink fountain 4, distributing rollers 5, form rollers 6 and an electric motor 7, which motor is independent of the bed reciprocating means and

drives both the distributing rollers 5 and the form rollers 6 continuously in one direction, to ensure an even application of the ink to the form 3, in the present instance on the reverse or non-printing stroke of the bed.

55

Any suitable means may be provided for lowering the form rollers 6 of the inking mechanism into position to ink the form 3 on the reverse or non-printing stroke of the bed, and for raising the form rollers 6 out of position to ink the form 3 on the forward or printing stroke of the bed. In the present instance said form roller raising and lowering means includes a cam plate 8 with yielding oppositely disposed end members 9, 10.

60

Fig. 15 The oscillating impression cylinder is denoted by 11 and its grippers by 12. This cylinder is driven in the usual manner from the reciprocating bed by the gear and rack 13, 14, the relation of the diameter of the cylinder to the movement of the bed being such that the cylinder is oscillated about one and one-half revolutions on each of its strokes. This impression cylinder is raised out of contact with the arm 3 on the return or non-printing stroke of the bed by the usual mechanism denoted by 15.

70

The feeder for the sheets is denoted by 16 and it may be of any well known or approved form. This feeder is arranged to feed the sheets to the under side of the impression cylinder 11 and it is provided with the usual stop 17 which may be operated at the proper time by the usual mechanism, not shown herein, to feed the sheet to the grippers 12.

85

The sheet delivery mechanism may be of any well known or approved form, that shown herein comprising a sheet stripper 18, the endless sheet carrier 19 and the coacting sheet delivery rolls 20, 21. The sheet delivery table 22 is denoted by 22. The sheet stripper 18 is arranged to strip the printed sheet tail end first from the upper side of the impression cylinder immediately after the start of the reverse or non-printing stroke of the cylinder.

95

The operation of the printing press is as follows: As the form bed and impression cylinder are started on their forward or printing stroke the impression cylinder grippers 12 will be closed on the head end of a sheet fed

100

from the feeder 16 and released by the sheet stop 17. As the bed and its form are moved in a right line to the end of their forward or printing stroke the impression cylinder will 5 be rotated about one and one-half revolutions to bring the tail end of the printed sheet slightly beyond its transfer point to the delivery mechanism as shown in Fig. 3.

As the bed and cylinder are started on their 10 reverse or non-printing stroke the impression cylinder 11 is raised by the mechanism 15 out of position to contact with the form, which movement also brings the stripper 18 into position to strip the tail end of the printed sheet 15 from the cylinder and direct it printed side up to the coating rolls 20, 21 of the delivery mechanism, which rolls then take control of the sheet. At the same time the form rollers 6 of the inking mechanism are lowered into 20 position to contact with the form and ink the same. When the impression cylinder has rotated a short distance on its reverse stroke, in the present instance about one-half of a revolution, the grippers 12 are opened to release the head end of the printed sheet. These 25 grippers are permitted to remain open during the remainder of the reverse or non-printing stroke of the impression cylinder.

From the above description it will be seen 30 that I have provided an inking mechanism for the above type of printing press in which the distributing and form rollers may be driven continuously in one direction independently of the bed drive and in which the form rollers 35 may be raised and lowered out of and into their form inking position. This continuous drive in one direction of the distributing and form rollers ensures a very even application 40 of the ink to the form.

It is evident that various changes may be resorted to in the construction, form and arrangement of the several parts without departing from the spirit and scope of my invention, and hence I do not intend to be limited 45 to the particular embodiment herein shown and described.

What I claim is:—

1. In a bed and cylinder printing press, a 50 bed and its form reciprocating in a right line, an inking mechanism including distributing and form rollers, means independent of the bed drive for driving the said rollers continuously in one direction only, and means for raising the form rollers out of the path 55 of the form on one stroke of the bed.

2. In a bed and cylinder printing press, a 60 bed and its form reciprocating in a right line, an inking mechanism including distributing and form rollers, means independent of the bed drive for driving the said rollers in one direction only, and means for raising the form rollers out of the path of the form on the printing stroke of the bed.

3. In a bed and cylinder printing press, a 65 bed and its form reciprocating in a right line,

an inking mechanism including distributing and form rollers, an electric motor for driving the said rollers continuously in one direction only independently of the bed drive, and means for raising the form rollers out of the path of the form on one stroke of the bed. 70

4. In a bed and cylinder printing press, a 75 bed and its form reciprocating in a right line, an inking mechanism including distributing and form rollers, an electric motor for driving the said rollers continuously in one direction only independently of the bed drive, and means for raising the form rollers out of the path of the form on the printing stroke of the bed. 80

In testimony, that I claim the foregoing as my invention, I have signed my name this 13th day of May, 1931.

CALVERT B. COTTRELL, 3D.
